CLAIM

The ornamental design for a pin the tail on the donkey party game, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a pin the tail on the donkey party game, in accordance with the present design.

The broken lines depict unclaimed features of the Pin the Tail on the Donkey Party Game, included for illustrative purposes only, that form no part of the design claim.
